BAG SUPPORTS

Ernest D. G. Garth, 23 Plymouth Road, Summit, N.J.

Filed Dec. 3, 1957, Ser. No. 700,432

5 Claims. (Cl. 248—95)

This invention relates to bag supports. More particularly, it is concerned with a support for the suspension of surgical bags and drain tubes at the sides of hospital beds.

The chief aim of my invention is to provide a simple and inexpensive support for the above purpose which is easily and quickly attachable to the bed, which is resistive to easy displacement when positioned on the bed, and from which the bag can be quickly removed after being emptied and replaced, or replaced by a new one.

Other objects and advantages will appear from the following detailed description of the attached drawings, wherein:

Fig. 1 is a perspective view of a surgical bag and drain tube support conveniently embodying my invention.

Fig. 2 is a view showing the support in vertical section and how the support is attached to the bed; and

Fig. 3 is a fragmentary view in perspective showing a modification.

From Figs. 1 and 2 of these illustrations it will be noted that my improved support comprises a horizontally elongate frame which, in practice, is fashioned from stout wire or any other suitably stiff strip material. The end members comprise somewhat irregular substantially inverted U-shaped portions 1 and 2 of which the longer frontal legs 3 and 4 are inwardly kinked as at 5 and 6 and are adapted to be engaged, as shown in Fig. 2, downwardly over and beneath one of the side rails R of a bed. The inwardly kinked portions form ledges for engagement with the underside of the rails. The longer frontal leg 3 of the inverted U-shaped end portion 1 is formed with a horizontal bar extension 7 over which a hem H along the top edge of a rectangular drainage bag B of transparent flexible material is impaled to sustain the bag in suspension. The pendant frontal leg 4 of the other inverted U-shaped end portion 2 of the frame is formed at the bottom with a retaining hook 8 into which the distal end of the bar 7 is sprung from above after application of the bag B to the bar as above explained. Somewhat above the hook 8, the pendant frontal leg 4 of the inverted U-shaped end portion 2 is fashioned with a double coil helix 9 between the convolutions of which the drain tube T leading from the patient in the bed is adapted to be frictionally engaged and thus held firmly and substantially vertically with the end of the tube passing down into the bag B through an opening C at one of the top corners of said bag. The engagement and disposition of the tube T is such as to insure free flow of fluid to the bag B.

When engaged over the side rail of the bed, the frame is held against easy displacement as will be readily understood from Fig. 2. When the bag B is full, the tube T can be easily and quickly detached from the coil 9

2

and withdrawn from the bag. With this accomplished, it will be apparent that the bag can be removed with equal facility from the bar 7 upon disengagement of the latter from the hook 8, and replaced, after being emptied or a new one be substituted for it.

In the modification, of Fig. 3, the bar 7a is separately formed and has a pivotal loop connection as at 10 with the pendant frontal leg 3a of the inverted U-shaped end portion 1a of the frame. In all other respects, the construction and use of the frame of the modification is identical with that of the frame illustrated in Figs. 1 and 2. Accordingly, in order to dispense with the necessity for repetitive description all of the elements of the modification, having their counterparts in the first described embodiment, are designated by the same reference numerals, with addition however in each instance, of the letter "a" for convenience of more ready distinction.

While in accordance with the provisions of the statutes I have illustrated and described two embodiments of my invention, it will be apparent to those skilled in the art that changes may be made in the form of the supports herein described and illustrated without departing from the spirit and scope of the invention, as set forth in the appended claims, and that in some cases certain features 20 of my invention may be used to advantage without a corresponding use of other features.

Having thus described my invention, I claim:

1. A bag support in the form of a wire frame having end members with inverted U-shaped portions for hooking downwardly over a side rail of a bed, and a horizontal, bag-holding, cross bar connecting said end members at their low extremities, one of said end members being fashioned in the region below its inverted U-shaped portion to form a clamp for a tube and having 30 opposed clamping elements disposed substantially vertically above the point of connection between the aforementioned end member and said cross bar.

2. A bag support as defined in claim 1 in which one end of the cross bar is fixedly connected to the lower extremity of one of said end members, and the other end of said cross bar is detachably connected to the lower extremity of the other end member.

3. A bag support as defined in claim 1 in which the tube clamping elements comprise convolutions of a wire 40 coil having its axis substantially paralleling the axis of the cross bar.

4. A bag support in the form of a wire frame having end members with inverted U-shaped portions for hooking downwardly over a side rail of a bed, and inwardly kinked portions providing ledges adapted to engage the underside of the rail, and a horizontal, bag-holding, cross bar connecting said end members at their lower extremities, one of said end members being fashioned in the region below its inwardly kinked portion to form a tube 50 clamp having opposed clamping elements disposed above the point of connection between the aforementioned end member and said cross bar.

5. A bag support as defined in claim 4 in the form of an integral, one-piece wire frame.
